United States Patent Office.

GEORGE B. GARLINGHOUSE AND CYRUS B. GARLINGHOUSE, OF NORTH MADISON, INDIANA.

Letters Patent No. 79,112, dated June 23, 1868.

IMPROVEMENT IN HARVESTER-PITMEN.

The Schedule referred to in these Letters Patent and making part of the same.

TO ALL WHOM IT MAY CONCERN:

Be it known that we, GEORGE B. GARLINGHOUSE and CYRUS B. GARLINGHOUSE, of North Madison, in the county of Jefferson, and State of Indiana, have invented a new and useful Improvement in Harvesters; and we do hereby declare the following to be a full, clear, and exact description of the same, reference being had to the accompanying drawings, in which—

Figure 1 shows a plan view of our invention.

Figure 2 a section (enlarged) on line $z z$.

Figure 3 the several parts of the same.

Our invention consists in an improvement in the construction and arrangement of the pitman-connection of a grain or grass-harvester.

The end of the pitman A, where it connects with the heel of the cutter-bar B, is turned at right angles, or a piece may be inserted in the end, projecting at right angles from it. This end is of a conical or conoidal form, and enters into a corresponding hole on the side of the heel of the cutter-bar. On the opposite side of the heel of the cutter-bar, and in the same axial line, is another conical or conoidal hole, similar to the first, which receives the conical end of the clamp D. On the front side of the pitman, and in the same axial line as the conical projection, is a conical hole, for receiving the end of the set-screw C. This clamp, in connection with the set-screw C, confines the end of the pitman-rod securely to the heel of the cutter, and is secured in position by the binding nut S, on the outside of the clamp. The clamp D, with its conical end bearing against and in the conical hole in the cutter-bar, and the end of the set-screw resting and bearing against the pitman, which in turn rests in the cutter-bar, gives the greatest freedom in turning on the centre, and at the same time permits the least possible play of the parts in the line of motion, and is very easily adjusted to take up any slack caused by friction and consequent wear of any of the parts in the operation of the machine, by simply tightening the set-screw C and its binding-nut S. The function and operation of the clamp will be the same whether it is arranged so that the end of the set-screw C bears against the pitman or against the heel of the cutter-bar.

In order that the cutter-bar may move truly, and not be raised from its proper place in operating the machine on uneven ground, we place upon the finger-bar, near the inner end of the cutter-bar, a holding-plate, F, and secure it firmly by screws. This plate projects over the upper surface of the cutter-bar, and forms a guide, to receive which a groove is cut upon the side of the heel. By this device the heel of the cutter-bar is effectually retained in its proper plane of movement, and by means simpler than those hitherto in use.

The pin H is inserted through a horizontal hole in the inner end of the guide-plate, and projects behind the heel of the cutter-bar, to prevent its accidental withdrawal, when the cutting-apparatus is folded for transportation. The pin H is retained in position by the spring L, which bears against its head.

Having described our invention, what we claim as new, and desire to secure by Letters Patent of the United States, is—

In the pitman connection with the cutter of a harvesting-machine, the single conical or conoidal pivot or point on the pitman, entering into a corresponding hole in one side of the knife-heel, in combination with the clamp, or its equivalent, arranged to work on the opposite side of the heel, on a centre coincident with the point of the pitman, for the purpose of affording free movement in turning on the centres, and to take up the slack caused by wear in working the machine.

In combination with the pitman and cutter-bar of a harvesting-machine, the separate detachable holding-device or clamp D, constructed as described, for the purpose of keeping the pitman in proper position with the knife-heel, and to be easily removed.

GEORGE B. GARLINGHOUSE,
CYRUS B. GARLINGHOUSE.
